DESIGN FOR A GAME BOARD

Lee Ornstein, Chicago, Ill.

Application March 19, 1945, Serial No. 118,585

Term of patent 14 years

(Cl. D34—5)

To all whom it may concern:

Be it known that I, Lee Ornstein, a citizen of the United States and a resident of Chicago, in the county of Cook and State of Illinois, have invented a new, original, and ornamental Design for a Game Board, of which the following is a specification, reference being had to the accompanying drawing, forming a part thereof, and in which

Fig. 1 is a top plan view of a game board showing my new design; and

Fig. 2 is an end elevational view of the same.

I claim:

The ornamental design for a game board, as shown.

LEE ORNSTEIN.
